UNITED STATES PATENT OFFICE.

JOHN MACLAURIN, OF BROOKFIELD, MASSACHUSETTS.

HAND SEALING-MACHINE.

1,177,528.

Specification of Letters Patent. Patented Mar. 28, 1916.

Application filed February 16, 1915. Serial No. 8,592.

To all whom it may concern:

Be it known that I, JOHN MACLAURIN, a citizen of Great Britain, residing at Brookfield, in the county of Worcester and State 5 of Massachusetts, have invented certain new and useful Improvements in Hand Sealing-Machines; and I do hereby declare the following to be a full, clear, and exact description of the invention, such as will enable 10 others skilled in the art to which it appertains to make and use the same.

This invention relates to sealing machines and more particularly to hand machines.

It has for an object to provide a machine 15 of this class which may be easily operated by a single hand and may be tilted to any position necessary for the application of sealing tape without spilling the liquid from the reservoir.

20 A further object of this invention is a provision of a moistening roller which is normally disposed out of contact with the sealing tape so that the gummed surface or the gumming liquid which may be applied 25 to the tape is not in contact with the moistening surface or adhesive applying surface.

A further object of this invention is a provision of an improved means for manipulating an improved form of cutting knife.

30 Further objects will be apparent from the following specification, appended claims and drawings in which,

Figure 1 is a vertical sectional view through the device embodying the features 35 of this invention, Fig. 2 is a plan view of the machine, Fig. 3 is a vertical cross sectional view as on the line 3—3 of Fig. 1, Fig. 4 is a similar view as on the line 4—4 of Fig. 1, and Fig. 5 is a bottom view.

40 In a device of this character, it is desired to have a compact machine which may be easily operated by a single hand of an operator and to have certain parts thereof so arranged that upon the removal of the operator's hand, these parts resume a normal position.

Referring to the drawings showing the 50 elements of this invention, 10 indicates a frame comprising a hollow wall in which liquid may be placed in the chamber 11. The side walls of the frame are connected by a trough 12 in which the liquid from the chamber 11 may freely pass and this trough is adapted to receive a moistening roller 13

which may be of any desired material, such 55 as brass or its equivalent. This roller is adapted to be swung about a pivot 14 as by a yoke 15 which supports journals for a shaft 16 and to which one end of a link 17 is pivotally connected as at 18. The opposite end of the link 17 is pivotally connected to a lever 19 as at 20 and this lever is connected to a handle 21 as at 22. When the operator's hand grasps the handle 21, the fingers include the lever 19 at which time 65 the roller 13 moves from the position shown in dotted lines in Fig. 1 to the full lines as shown, when the surface of said roller contacts with the face of the tape 23 to apply moisture to said tape in the event of its 70 having a gummed face, or to apply adhesive to the face of said tape when said tape is ungummed.

The device is provided with a feeding roller 24 and applying roller 25 which serve 75 as supports for the machine and also as pressure rollers for the tape being applied to an article. The roller 24 is adapted to receive the tape 23 as shown, after said tape passes a guide 26 upon passing through an opening 27 formed in the frame and said tape may come from a roll not shown supported in any desired manner. The roller 25 is adapted to receive the tape after it has been rendered adhesive by its contact with the roller 13 80 and this roller 25 is adapted to feed the treated tape for application upon an article as well as to press said tape firmly against the article. It is provided with a gear 28 which meshes with an idler 29 which is in 90 mesh with a gear 30 carried by the shaft 31, to which the pressure roller 32 is secured. By this train of gears, the roller 32 moves in unison with the roller 25 and the roller 32 is so positioned as to receive pressure exerted by the roller 13 pressing against the tape 23 to assure the proper application or treatment of the tape 23 as it passes the roller 13.

To restrict the rotation of the roller 25 to 100 one direction and likewise to limit the movement of the frame 10 to one direction, the shaft 31 is provided with a ratchet 33 the teeth of which a pawl 34, pivoted to the frame 10, is adapted to engage. This pawl 105 is normally held in engagement with said ratchet as by the spring 35.

After the desired amount of tape has been

applied, to the article, the applied portion may be severed from the supply by a spiral knife 36 which is formed on a roller 37 journaled upon a stub shaft 38 and this stub shaft is held in the lower end of the lever 39 which is pivoted as at 40 so that said knife may be brought into contact with the tape as it passes the roller 25. The lever 29 extends above the pivot 40 and has its upper end connected as by a link 41 to one end of a handle 42 which is pivoted as at 43 to the handle 21. The handle 42 is returned to normal position as by a spring 44.

In use, the tape is threaded through the machine as shown and when it is desired to apply a portion thereof to a package or the like, the lever 19 is raised to raise the roller 13 to apply liquid to said tape before it passes about the roller 25. The handle is held in raised position and the application of the tape may be continuous until the desired amount has been applied, after which the handle 42 may be depressed when the spiral knife 36 may sever the tape as is obvious. In applying the tape to a package, it is frequently desired to tilt the machine to contact with the vertical sides of the package at which time, the liquid will flow from the trough 12 into the chamber 11 in any position of the machine so that the throat of the trough 12 will not form an outlet for any of the liquid except as applied by the roller 13 when the machine is in horizontal position. Furthermore, the knife 36 cuts the tape at an angle to afford a reduced end on both ends of the tape so that the reduced end of the section of the tape applied to an article affords a more perfect application of the tape, while the reduced end remaining in the machine affords a guide to direct the tape for further application.

Various modifications may be made with respect to the several parts including the proportions and relative positions of the several parts, without departing from the spirit of the invention and it is thought that the operation of the device is clear in view of the foregoing.

Having thus described my invention, I claim:

1. In a sealing machine, a frame, a handle formed on said frame, a series of rollers supported by said frame, said rollers being adapted to receive a sealing tape thereabout, a movably mounted moistening roller carried by said frame, said moistening roller being adapted to engage the sealing tape in one position thereof and to be swung from engagement therewith in the opposite position, and a lever pivotally secured to said handle having communication with said moistening roller.

2. In a sealing machine, a frame, a handle formed on said frame, a series of rollers sup-

ported by said frame, said rollers being adapted to receive a sealing tape thereabout, a ratchet mechanism for limiting the rotation of some of said rollers to one direction, a movably mounted moistening roller carried by said frame, said moistening roller being adapted to engage the sealing tape in one position thereof and fall from engagement therewith in the opposite position, a lever pivotally secured to said handle having communication with said moistening roller, and a cutter movably carried by said frame adapted to sever the sealing tape when desired.

3. In a sealing machine, a frame, a series of rollers carried by said frame, said rollers supporting said frame and being adapted to receive a sealing tape thereabout, one of said rollers having a limited movement in one direction only, a trough formed in said frame, and a moistening roller yieldably carried by said frame, having a movement through the throat of said trough to engage or disengage said tape.

4. In a sealing machine, a frame, rollers 90 carried by said frame to support the same, and adapted to receive a sealing tape thereabout, a trough formed in said frame, a moistening roller movable through the throat of said trough and said frame having tubular 95 walls to form a chamber to receive a liquid for treating the tape, said chamber having communication with said trough.

5. In a sealing machine, a frame, a handle formed on said frame, said frame having a tubular wall to form a liquid receiving chamber, a trough formed in said frame having communication with said chamber, rollers carried by said frame adapted to receive a sealing tape thereabout, a moistening roller 105 movably carried by said frame through the throat of said trough, a lever carried by the handle of said frame having connection with said moistening roller, a cutter carried by said frame, a supplemental handle carried by the handle of said frame, said supplemental handle having connection with the support for said cutter, and manipulation of said supplemental handle causing said cutter to sever the sealing tape when desired.

6. In a sealing machine, in combination with a trough to receive a liquid, a moistening roller movable through the throat of said trough, said trough being adapted to receive 120 a sealing tape across the throat thereof, said moistening roller being movable to engage the tape and means to receive and apply the tape.

7. In a sealing machine, a frame, said frame having tubular walls to form a continuous chamber thereabout, to receive a liquid, a trough connecting the opposite side walls of said frame, said trough having communication with the interior of the 130

liquid chamber, said liquid chamber having proportions of sufficient volume to receive the liquid from said trough, and the opposite sides of said chamber when said frame 5 is tilted from a horizontal position and rollers carried by said frame for receiving, moistening and applying a sealing tape.

In testimony whereof I affix my signature in presence of two witnesses.

JOHN MacLAURIN.
